UNITED STATES PATENT OFFICE.

EDWARD M. CHADBOURNE, OF SAN FRANCISCO, CALIFORNIA.

OIL-CONCRETE ROADWAY.

965,562.

Specification of Letters Patent. Patented July 26, 1910.

Application filed February 12, 1910. Serial No. 543,557.

To all whom it may concern:

Be it known that I, EDWARD M. CHADBOURNE, a citizen of United States, residing at the city and county of San Francisco and State of California, have invented new and useful Improvements in Oil-Concrete Roadways, of which the following is a specification.

This invention relates to highway construction, and pertains especially to an oiled, reinforced concrete road.

The object of the present invention is to provide a road, street or way which is made of a substantial sub-base and a wearing cushion which is dustless, permanent, and requires very little expense for maintenance.

The special object of the present invention is to construct this roadway so that the wearing surface, which is made up of a mixture of oil, or like binder, and screenings, and is permanently anchored to the underneath foundations and base, is rejuvenated or revitalized whenever the surface begins to break up or disintegrate, by the elastic element of a certain surplus of a natural liquid binder, or a binder which is liquid or viscid at ordinary temperatures.

A street or highway is a structure built ordinarily, as is well known, to endure or sustain the traffic of moving vehicles, such as automobiles, traction engines, wagons, etc. This traffic creates forces or loads which a street or highway must be designed to withstand, according to conditions or requirements of use. Among these forces or loads are the forces of impact which are created by sudden shocks or blows delivered to the street or highway from external bodies. These shocks or blows may be delivered by heavy trucks, traction engines, horses, etc., their effect being impact forces which tend to disintegrate whatever they come in contact with. Therefore, one of the essential requirements for a good street or highway is that it must be able to absorb shocks or blows through a wearing surface having elastic properties. In the selection of material for the wearing surface to absorb this force of impact there are many materials in use today, such as bitumen, asphaltic compositions, brick, wooden blocks, etc. Of these materials asphaltic compositions and bitumen are used the most for wearing surfaces, but on account of their properties they cannot absorb impact forces.

Consequently, they eventually disintegrate, and the street or highway fails because the binder used is a naturally solid or non-viscous material. I mean by this that its natural state is not a liquid, but is a solid, such as the asphalt and asphalt compositions commonly used. Hence, to give them binding properties they must first be heated to a liquid form and then applied in combination with other materials, such as sand, rock, etc. When this binder cools off, it solidifies and holds the different particles which it surrounds rigidly, with the result that surfaces made up of naturally solid binders are inelastic and will not stand impact forces.

In my invention which has resulted after many experiments and demonstrations, I use naturally liquid binders and so place them that they always exert binding forces into the wearing surface, giving it elasticity and ability to absorb impact forces. In placing and holding this naturally liquid binder, I have taken into consideration a very important point, and that is, that knowing that the naturally liquid binder will flow out in a way from the aggregate in wearing surfaces, I have taken special pains to arrange my roadway so that the naturally liquid binder is forced into, and a certain excess of the binder retained in, the voids in the aggregate of the wearing surface, with the result that my surface is elastic and able to absorb impact forces.

Correlative with the desideratum of elasticity is that of tenacity, or the quality to resist the forces of suction due to the rapid travel of modern automobiles and the like, and the quality of resisting the wear and disintegrating action of the elements and climatic conditions. My roadway fulfills these requirements also.

My invention purports the construction of a roadway with a surface that is as nearly perpetually elastic as possible, and also a surface that may, when oxidized or worn out, have its vitality and elasticity restored, from a storage of oil, or equivalent, in reservoirs or pockets in the surface of the base and also from the oil in the voids in the screenings in the top surface.

Having reference to the accompanying drawings—Figure 1 is a perspective view in partial section of a roadway illustrating the invention. Fig. 2 is a section in a vertical

110

plane, and Fig. 3 is a sectional perspective of roadways showing modifications in the formation of the pockets.

A base of plain or reinforced concrete A 5 is first laid. Before this concrete base is set, and while it is still in a plastic condition, I form pockets or reservoirs in the same in several different ways. One way is by placing on top of this concrete base, 10 while it is still plastic, a course of large rock 2 approximately two to three inches in size. A good part of this course of rock becomes attached to the concrete base, when it sets, while between the individual rocks 15 pockets or reservoirs are formed, which will hold oil or equivalent naturally liquid or semiliquid binder. In many cases where large rock is not available, I may press into the surface of this concrete base, when plastic, a form having small knobs on the under side, and when the same is removed after the concrete is set, pockets or reservoirs 20 are formed, as shown in Fig. 2. In many cases I may vary the size of the storage reservoirs, making them the width of the roadway, or I may make them as small as two inches in width dimensions. In all cases the depth of these pockets or reservoirs is 25 approximately one to three inches. If very little crown is desired for the roadway, and if the same is nearly level, I may form in the concrete base furrows or canals which serve the same function as pockets or reservoirs. In any case, all of the indentations, 30 grooves, pockets or receptacles in the concrete base, no matter in what size or form they are placed or by what means made, serve as storage reservoirs for the oil. After the concrete base is set and the 35 pockets or reservoirs become formed therein by any suitable method, I flood this base with, or apply to the surface of the base a coating of heavy, mineral oil; which, if heavy asphaltic oil is used, may be previously heated to make it more viscous. This oil fills, or partially fills, the pockets or reservoirs in the top of the concrete base, and on account of the impervious compositions in the base does not percolate downward and become lost. I next spread a 40 layer of sized screenings over the oiled concrete base, these screenings being approximately one-half inch in size. These screenings are as near one size as possible, as I thus obtain a larger percentage of voids in 45 same. These screenings not only fill the pockets, but extend two or three inches, more or less, above the surface of the base, according to the desired depth of the finished wearing surface. The screenings are 50 then rolled, forcing the screenings down into the oil, partially displacing the oil binder and forming a permanent finished 55 wearing surface that is elastic, tenacious and durable. One size of screenings is suffi-

cient, as I have found that clean screenings of approximately half-inch size give excellent results; and the wear that their surface is subjected to keeps the upper interstices filled, and as the oil works upward constantly it binds the whole surface into one monolithic structure possessing the desirable attributes of elasticity and permanency. With these sized screenings there is a certain amount of oil in the pockets that 60 is not absorbed at first, and I purposely use these sized screenings so as to make a great many small distinct voids to provide oil cavities. The excess oil in the pockets or reservoirs on top of the concrete base, and 65 also in the voids in the screenings, makes the surface as near perpetually elastic as possible, for the reason that as soon as the wearing surface hardens and oxidizes out and starts to wear away, the liquid binder 70 in the pockets or reservoirs in the top of the concrete base and also in the voids in the lower course of the screenings in the surface rejuvenates or revitalizes the wearing surface so that it is made elastic again. It is 75 thus seen very readily that as soon as one surface of the roadway disintegrates and wears away, another forms by the action of the stored oil lubricating and rebonding the 80 screenings again. This wearing surface 85 wears away far less rapidly than a wearing surface which has no storage of oil to rejuvenate or revitalize it, and give it elasticity when exhausted.

A roadway which is thus constructed comprises a concrete or like impervious base 90 with pockets in its top surface, with a layer of sized screenings thereover, and with a bond of heavy oil or equivalent naturally liquid binder, the amount of the liquid 95 binder being in excess of that necessary to coat and cement the screenings, this excess being contained in the voids formed by the screenings and lying on top of the concrete base and filling the pockets; the screenings 100 being rolled to form a firm wearing surface, and the excess of binder contained in the voids gradually working to the surface to 105 rejuvenate the latter as time goes on.

While I prefer to use, for commercial 110 reasons, a heavy asphaltic oil, I may use any other naturally viscous, or live liquid or semi-liquid binder, this binder being first 115 poured in natural fluid state, or slightly heated to increase its limpidity, over the impervious foundation, and then spreading the aggregate in the form of sized screenings 120 over this liquid binding stratum; this binder having the quality, after the aggregate is rolled to form a wearing surface, of not only binding the particles together, but of gradually oxidizing or hardening from the surface downward, drawing up to the 125 surface through the course of time the vitalizing element of the remaining or sur-

plus liquid binder contained in the voids or pockets beneath, so that the surface of the roadway is undergoing constantly an automatic rejuvenation to give it permanence and elasticity.

The concrete base, which may or may not be reinforced, forms a rigid, monolithic, durable sub-structure to distribute a live or dead load over the subsoil. The aggregate forming a wearing surface together with the liquid binder gives the desired elasticity and tenacity.

I prefer to use aggregate in the form of irregular sized screenings, since the irregular surfaces tend to interlock and consequently prevent motion about each other when acted on by external forces. Also, as it is advisable to have as much oil or other natural liquid binder in the wearing surface as possible, the percentage of voids in the screenings must be large, and for that reason I prefer to use the screenings of approximately half-inch size, with the result that the voids average about forty per cent. of the volume; this forty per cent. of volume being occupied by the excess of the binder, which excess, as before described, is utilized, when necessary, to revitalize the wearing surface by giving it renewed elasticity and bonding qualities.

Having thus described my invention, what I claim and desire to secure by Letters Patent is—

1. A method of roadway construction which consists in laying a foundation impervious to heavy oils and forming its surface into receptacles to prevent escape of the oil by drainage and in applying to said foundation a top layer of oil and small size aggregate having a large percentage of voids filled by the oil, the percentage of oil being in excess in the bottom of the top layer in position to be supplied to the wearing surface by absorption.

2. The method of roadway construction which consists in laying a concrete foundation impermeable to liquids and forming the upper surface of said foundation into receptacles open at the top to retain a natural liquid binder against escape by drainage, applying a natural liquid binder to said foundation, then applying and forcing down into said binder small aggregates to form a layer having its voids filled by the binder, the relative percentage of aggregates and binder being such that the binder is in excess in the layer of aggregates and in position to be absorbed by the wearing surface of the roadway to revitalize the latter.

3. The method of roadway construction which consists in forming a concrete foundation over the roadway, forming pockets in

the top of this foundation, flooding the surface and pockets with a heavy oil, applying a layer of sized screenings and forcing the same down into the pockets and oil, said screenings and pockets forming numerous voids to store a surplus of oil, the relative percentage of screenings and oil being such that the oil is in excess and in position to be absorbed by and rejuvenate or revitalize the wearing surface.

4. The method of roadway construction which consists in laying a concrete foundation, and while the latter is in a plastic condition forming oil retaining pockets open at the top, pouring a coating of heavy asphaltic oil over the surface to fill the pockets, spreading a layer of screenings approximately one-half inch in size over the foundation, and rolling the screenings to compress them and to fill the pockets, the relative percentage of oil and screenings being such that the oil is in excess and said screenings forming a multiplicity of voids which act as storage reservoirs for the surplus of oil which is not taken up by absorption, said surplus of oil acting to rejuvenate the wearing surface as time goes on.

5. The method of roadway construction which consists of laying a concrete foundation, and forming its surface into numerous pockets or reservoirs, pouring over the surface of the foundation a naturally liquid binder sufficient to fill the pockets, then spreading a layer of sized aggregate over the surface, which layer of aggregate forms within itself numerous voids and the percentage of oil being in excess of that which will be held by absorption in the aggregate, the aggregate filling the pockets and extending over the foundation, and rolling this aggregate to compress it and to take up a portion of the binder to provide a wearing surface.

6. A pavement for roadways embodying a cementitious foundation impervious to heavy oils fluid at ordinary temperatures and embodying means for preventing the escape of oil by drainage, a top stratum of comminuted wear resisting material overlying said foundation, and a heavy oil fluid at ordinary temperatures held in said top stratum and existing in excess in proximity to the foundation, whereby the oil will be maintained in position to be fed to the wearing surface by absorption.

In testimony whereof I have hereunto set my hand in the presence of two subscribing witnesses.
